R. O. Smith

UNITED STATES PATENT OFFICE.

CHARLES MCNEAL, OF MISHAWAKA, INDIANA, ASSIGNOR TO WALLACE H. DODGE, OF SAME PLACE.

WOODEN PULLEY.

SPECIFICATION forming part of Letters Patent No. 351,064, dated October 19, 1886.

Application filed April 2, 1886. Serial No. 197,563. (Model.)

To all whom it may concern:

Be it known that I, CHARLES MCNEAL, of Mishawaka, in the county of St. Joseph and State of Indiana, have invented new and useful Improvements in Wooden Pulleys; and I do hereby declare that the following is a full and accurate description of the same, reference being had to the accompanying drawings.

Wooden pulleys are generally constructed by gluing together a series of wooden rings, which together constitute a ring having the requisite diameter and width of face. A hub and spokes or arms are inserted, sometimes during the process of building up the ring and sometimes subsequently.

My present invention relates particularly to that class of pulleys known as "wooden pulleys," some of which are separable through the hub and known as "split pulleys," Letters Patent No. 260,462 having been granted to Wallace H. Dodge and George Philion and Letters Patent No. 276,230 granted to W. H. Dodge for pulleys of this class; and it consists, first, in the hereinafter-described lock-joint at the separable ends of the segments; second, in the tapered, dovetail, and wedge joint uniting the end of the spoke with the pulley-rim; third, in a stay-brace for pulleys of large size.

Figure 1 is a perspective view of the adjoining ends of the two parts of my pulley separated, showing the lock-joint. Fig. 2 is a perspective of the end of one of the arms or spokes, showing the wedging dovetail. Fig. 3 is a perspective view showing pulley-rim at the period when the spokes are inserted and the lock-joint is formed. Fig. 4 is a perspective view, partly in section, showing the manner of inserting the wedging dovetailed arm or spoke in the rim and the fastening-wedge. Figs. 5 and 6 represent the manner of inserting the stay-bolt.

A is the rim of the pulley, built up of successive rings glued together with the grain crossing to insure strength and permanency.

The method pursued in constructing the pulley to produce the lock-joint at the separable points is as follows: A sufficient number of rings *b b* to form about one-half of the pulley are glued together, as shown in Fig. 3, and then with a band or jig saw the rim is divided

transversely on an irregular line—say like the line *d*, Fig. 3—so that there is on one side a depression or hollow and on the other side a projection which exactly matches in and fits said depression. The arms or spokes *C* are then inserted and fastened securely to the pulley-section so constructed. Other rings, *e e*, are then glued fast to the divided rim, the parts of which have been put in proper position, separated by pieces of paper or other proper material having a thickness equal to the sawkerf. This completes the pulley to full width, with the ends of the arms or spokes *C* buried in the rim. The outer rings, *e e*, are then divided with a straight saw, as shown in Fig. 1, 65 and the separable ends are thus provided with an interlocking joint, by which the two adjoining parts are kept in constant and proper relative position under all circumstances. After having been built up and the pulley-rim divided, as above described, the fastening-bolts *f* are inserted, the hub is bored, and the pulley-rim turned up true and finished. 7c

The second part of my invention relates to the manner of inserting the ends of the arms *C*, 75 whether the rim is divided or not. Each end of each spoke *C* is cut so as to constitute a dovetailed tenon, *g*, but so that said tenon is wedging or narrower on one edge than on the other, as shown in Figs. 2 and 4. A straight 80 or parallel sided dovetailed mortise, *h*, is cut transversely on the inner surface of the rim for each spoke end, and when properly inserted in said mortises the dovetailed tenons *g* fit said mortises on one side, but have a wedge-shaped 85 recess on the other. This recess is filled with a wedge, *i*, which firmly secures all the parts with a perfect fit, and when properly glued the arms and rim constitute a solid structure. The number of arms so inserted may be greater or less, 90 as desired.

In pulleys of large size, or those designed to transmit great power, I prefer to insert stay or brace bolts *K*, extending from the ends of the arms or spokes back into the rim and 95 rigidly secured there, so that the portion of said rim between the end of the spoke and the end of the pulley-section shall be relieved from the thrust or pressure of said spoke. The attachment of said bolt to the rim may be made 100

in any suitable way; but I prefer to prepare a cylindrical pin, L, provided with a seat for the head of the bolt K, and insert said pin in a cell or socket in the inner surface of the pulley-rim, said cell being deep enough to receive said pin and seat for the bolt-head and firmly anchor said bolt in the substance of said rim. The bolt K thence extends through the arm C, and a screw-nut on the bolt strains said arm 5 back toward said pin L, and causes the thrust or pressure of said arm to be transmitted to the pulley-rim independent of the portion of wood, m, between said arm and the end of the pulley-section.

15 Having described my invention, I claim as new—

1. The mode or procedure in building a wooden split pulley herein described, which consists in first building the central part of 20 said rim; second, in dividing the same transversely on an irregular line to make an interlocking joint; third, in adding a section to each edge of said central part and dividing the same with a straight saw, whereby the adjoining ends of the rim are provided with interlocking portions, as set forth.

2. A wooden split pulley provided with interlocking projections and recesses in the ad-

joining ends of the rim formed by dividing the same on a curved line, substantially as set forth.

3. A pulley provided with an arm or spoke, C, having at its ends the wedging dovetailed tenons g, fitting in a dovetailed mortise, h, in the pulley-rim, and the fastening-wedges i, substantially as set forth.

4. A separable wooden pulley having its rim divided on an irregular line to form interlocking portions at adjoining ends, and having its spokes or arms at their outer ends embedded 40 in the rim with dovetailed tenons and mortises, substantially as set forth.

5. A split pulley having a section, A, and the arm C, mortised into the same near its end, and provided with a stay-bolt, K, extending from said arm back to the pulley-rim at a distance from its end, substantially as set forth.

6. A split pulley having the rim A and the arm C, mortised into the same near its point of division, and provided with the stay-bolt K 50 and the anchoring-pin L, inserted in the rim, as set forth.

CHARLES McNEAL.
